MEANS FOR GRINDING CARD FLATS

Orville L. Hope, East Gastonia, N. C.

Application March 8, 1937, Serial No. 129,644

2 Claims. (Cl. 51—243)

This invention relates to a card grinding apparatus for grinding card flats and more especially to means for properly positioning the flats relative to the card grinder as the flat teeth are ground thereby. In the grinding of card flats it has been the practice to guide the upper portion of each end of the flats as they pass beneath the grinding cylinder by a pair of slides. These portions were held in sliding contact with said slides by means of suitable pressure applying means such as dogs which engaged the lower side of the flats at two intermediate points, each of the intermediate supporting points being an appreciable distance from the end of the flats. In order to exert sufficient upward pressure at each point to normally hold the upper side of the card flat against the two slides, an appreciable amount of upward deflection was caused in the central portion thereof thereby causing the teeth in this central portion to be ground more than the teeth at each end. This practice causes what is commonly known as hollow flats which in turn, causes defective carding when they are in operation with the carding cylinder.

It is therefore, an object of this invention to provide an apparatus for grinding the teeth on card flats comprising a grinding cylinder, with guiding means for positioning the flats in grinding relation thereto and a pair of weighted supporting means disposed at each end and on the lower side of said flats directly opposite said guiding means for holding the card flats in proper position relative to said guiding means and said grinding cylinder. By providing the supporting means oppositely, or directly beneath said guiding means, it is evident that the amount of pressure exerted by the supporting means will not in any way cause the central portion of the card flat to be deflected upwardly. Therefore, it is only necessary to provide an intermediate supporting means to compensate for the weight of the flat itself. This is done, where necessary, by providing a weighted support directly beneath the central portion of the flat to prevent any downward deflection thereof. Should the upward supporting means be disposed several inches from each end of the card flat and if only enough upward pressure is exerted thereon to compensate for the deflection due to the weight of the flat itself, then this upward pressure would not be sufficient to hold the top ends of the flat in contact with the guiding means during the grinding operation.

It is a further object of this invention to provide a card flat having supporting means be-

neath each end thereof normally pushing its ends against a pair of guiding means, said guiding means comprising a pair of stationary beveled surfaces which cause the flat to be so positioned that each of the teeth in the upper side of the card flat will occupy the same position relative to the grinding cylinder as the card flat passes thereby.

Some of the objects of the invention having been stated, other objects will appear as the description proceeds, when taken in connection with the accompanying drawings, in which:

Figure 1 is a side elevation of a portion of a card machine showing my invention applied thereto;

Figure 2 is a cross sectional detail view through the carding machine taken along the line 2—2 in Figure 1;

Figure 3 is an enlarged detail view of the end of card flat grinding apparatus which is also shown in Figure 1;

Figure 4 is a vertical sectional view taken along the line 4—4 in Figure 2;

Figure 5 is a sectional plan view taken along the line 5—5 in Figure 3;

Figure 6 is an isometric view of the supporting means for the other end of the card flats from that shown in Figures 3, 4, and 5, one of the supporting means being shown in the left-hand portion of Figure 2;

Figure 7 is a vertical sectional view taken along the line 7—7 in Figure 2;

Figure 8 is an enlarged detail view looking at the end of the flat showing its position relative to the supporting means, guiding means, and grinding cylinder when the flat is passing beneath the grinding cylinder.

Referring more specifically to the drawings, the numeral 10 denotes the framework of a suitable card machine which has rotatably mounted as at 11, a card cylinder 12 which has teeth 13 therein, which normally cooperate with the teeth 14 in card flats 15 during a carding operation. The framework 10 has mounted at one end thereof a lap roll 16 which is fed beneath feed roll 17 into licker-in chamber 18 and then between the card cylinder 12 and the card flats 15 to card the fibers and remove foreign matter therefrom and to align the fibers. The card flats 14 are secured to suitable chains 20 and 20', said chains being mounted on suitable conventional rollers 21, 22, 23, and 24, which, in turn, are supported by brackets 25, 26, 27 and 28, respectively.

After continued use, it is necessary to sharpen

55

the teeth 14 in the card flats; therefore, a suitable grinding mechanism has been employed, comprising a pair of supporting stands 30 and 30' which have brackets 31 and 31' adjustably secured to the upper end thereof by any suitable means such as bolts 32 and 32' respectively. The bolts 32 and 32' clamp the brackets 31 and 31' to their support and the bolts 33 and 33' hold the brackets 31 and 31' in the adjusted position. 10 The brackets 31 and 31' are adapted to support a suitable shaft 35 upon which is mounted a grinding cylinder 36. Suitable guides 37 and 37' are secured to supporting stands 30 and 30' by means of bolts 38. Fixedly secured to the lower 15 surface of said guides are beveled strips 39 and 39' which strips normally guide the top surfaces 40 on each end of the card flats, when the card flat is in grinding position. Disposed directly beneath the beveled strips 39 and 39' and 20 also directly below the ends of card flat 14 are supporting means 42, 43 and 42' and 43', the supporting means 42 and 43 being adapted to support the right-hand end of card flat 14 as 25 shown in Figure 2, and the supporting means 42' and 43' being adapted to support the left-hand end thereof.

Levers, or supporting means 42 and 43 are fixedly secured to stud shafts 44 and 45 which in turn, are rotatably mounted in end support 30. 30 The other ends of shafts 44 and 45 have fixedly secured thereon levers 48 and 49 which have weights 50 and 51 respectively, adjustably secured on the ends thereof. By regulating the distance at which a weight 50 or 51 is located relative to 35 the stud shafts 44 and 45, the amount of upward pressure exerted by the supporting means 42 and 43 can be effectively regulated. The construction of the weighted levers 42' and 43' is identical, and therefore, no description will be made, 40 but like reference characters with prime notations will be given to like parts.

The supports 30 and 30' have integral therewith lower guide supports 55 and 56 which support the lower ends of the card flats 14 prior to 45 their approach to grinding position and after they have passed beyond the grinding position. While the card flats are in grinding position, the supporting means 42 and 43 flexibly support the flat in a position where the surfaces 40 and 40' 50 will engage the lower side of bevel strips 39 and 39' respectively.

It is necessary to provide a pair of weighted supports such as 42 and 43 beneath each end of the card flat when the same is in grinding position because of the irregularity of the construction of the lower side of each end. If only one dog were provided a uniform upward pressure could not be exerted under the entire breadth of the flat ends so that the upper surfaces 40 and 40' 55 of the flat would be held in firm contact with strips 39 and 39'. It is also necessary to overlap the free ends of pressure applying means 42 and 43 so that both members will simultaneously engage the ends of the flat from the time it 60 comes to grinding position until after it has been ground.

When it is desired to effect a grinding operation, a belt 60 is mounted upon pulleys 61 and 62, and the cylinder 36 is caused to rotate in a 70 counter-clockwise manner in Figures 1, 3, 7 and 8. At the same time the weights 50 and 51 and their associated parts are placed in their proper position in order to exert the proper upward pressure beneath the lower ends of the flats. The flats 14 are then caused to rotate in a counter-

clockwise manner in Figure 1 to thereby cause the top ends of the teeth 14 to engage the periphery of grinding cylinder 36 in a manner shown in Figure 8. It will be noted by referring to Figure 9 that since the surfaces 40 on the end 5 thereof normally engage the lower beveled surface of the strip 39, which is shown in dotted lines, the end of the card flat will gradually move downwardly away from the grinding cylinder as the flat is moved to the left in the direction of 10 the arrow; however, it will also be noted that the point of each of the teeth will be ground exactly at the same angle, although, the teeth in the left-hand edge of the flat are slightly shorter than the teeth on the right-hand edge thereof. 15 This difference in length is very much exaggerated in the drawings in order to properly illustrate the principle involved. By so grinding the teeth in the card flat in this manner, when the teeth are placed in carding position as shown in the 20 lower portion of Figure 7, the long teeth on the right-hand side of the flat in Figure 8 are disposed at the same distance from the card cylinder teeth 13 as the short teeth, since the beveled upper ends 40 and 40' rest upon the flexible 25 arch supports 63 and 63' on each side of the card cylinder, the periphery of the arch supports being concentric with the periphery of the cylinder teeth. By grinding the flat teeth in the manner shown in Figure 8 the proper point is 30 ground on each individual tooth and the pointed ends on all of the teeth fall in a plane which is parallel to a plane passing through top beveled surfaces 40 and 40'. By so grinding the heel and toe will be equidistant from the card cylinder when in operative position.

The dotted line 65, in Figure 8, represents the line along which the dogs 42 and 43 exert upward pressure upon the lower side of flat during 40 the grinding operation.

In order to compensate for the deflection caused by the weight of the flat 14 a suitable cross bar 66 has its ends fixedly secured in the supports 30 and 30'. Secured to the central portion of bar is a bracket 67 by any suitable means 45 such as bolt 68, said bracket having pivoted as at 69 a lever 70. This lever has the left-hand portion thereof, (Figure 7), extending upwardly and normally engaging the lower intermediate portion of the flat 14. Where the flats have been 50 properly designed as to strength it is seldom that this pressure applying means is necessary; however, in case of a very weak structure where the stress caused by the grinding and the initial weight of the flat will cause downward deflection 55 in the central portion thereof, it is necessary to provide a lever 70 pivoted as shown with a suitable adjustable weight 71 secured on the end thereof. It is quite evident that if there is a deflection of the flat in the central portion 60 thereof, that this point is the proper place to apply the weight to remedy the defect.

As heretofore stated, should the weight be applied at a short distance from each end, then 65 at least two of such devices as shown would be necessary and at the same time it would be very much harder to determine the amount of upward stress necessary at these points to produce the desired upward deflection at the central portion thereof; however, it would also be necessary to add additional stress for holding the ends 40 and 40' in contact with strips 39 and 39'. This additional stress, of course, would cause an objectionable upward deflection at the 75

center of the flat and cause the teeth at the point to be ground more than necessary.

It is therefore seen that I have provided a card grinding apparatus for grinding flats, said apparatus comprising a pair of guide ways for properly positioning each flat as it passes by the grinding cylinder and means disposed directly below the flat ends and said guiding means for exerting upward pressure against the lower ends of the flat to hold them in the proper position relative to the cylinder.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

- 20 1. In a carding machine having a carding cylinder equipped with card clothing provided with teeth and having a pair of endless chains to which the flats are secured and said flats having teeth therein for cooperation with the teeth on the card clothing, apparatus for grinding the teeth on the flats comprising a grinding cylinder disposed transversely of the machine and in alinement with the flats, fixed cam means for engaging the upper surfaces of the extremities of the flats as they approach and move past the grinding cylinder, a pair of weighted, pivoted and oppositely directed levers having side by side cam portions for engaging the extremi-
- 25 ties of the flats in the same vertical plane in which said fixed cam means are disposed to hold the flats against said cam means while the teeth thereof are engaged by said grinding cylinder, and means for engaging the central portion of the flats for holding their central portion in the same horizontal plane occupied by the extremities of the flats while the flats are in grinding position.
- 30 2. In a carding machine having a frame, a carding cylinder and a pair of endless chains to which a plurality of toothed flats are secured, apparatus for grinding the teeth on the flats comprising a pair of brackets secured to the sides of the frame, a fixed cam on each bracket for engaging the extremities of the flats as they are moved past the cams, a grinding cylinder for engaging the teeth in the flats, a pair of pivoted levers having side by side end portions disposed in parallel relation and having cam surfaces thereon for engaging the extremities of the flats on their lower sides in the same vertical plane as that occupied by the said fixed cams, a weight on each lever for holding the said parallel end portions against the said flats to press the extremities of the flats against said cams while the flats are being passed beneath the grinding cylinder and a pivoted lever having a weight on one end and a cam surface on the other end for engaging the central portion of each flat as it is moved beneath the grinding cylinder.

ORVILLE L. HOPE.
